UNITED STATES PATENT OFFICE.

WALTER FRENZ, OF NEW YORK, N. Y., ASSIGNOR TO NEW YORK BUTTON WORKS, OF NEW YORK, N. Y., A CORPORATION OF NEW YORK.

DESIGN FOR A BUTTON.

No. 40,102.

Specification for Design.

Patented June 29, 1909.

Application filed May 1, 1909. Serial No. 493,442. Term of patent 3½ years.

To all whom it may concern:

Be it known that I, WALTER FRENZ, a citizen of the United States, residing at 264 Canal street, borough of Manhattan, in the county of New York and State of New York, have invented a new, original, and ornamental Design for Buttons, of which the following is a specification, reference being had to the accompanying drawing, forming part thereof.

Figure 1 is a plan view, and Fig. 2 an edge view of a button showing my new design.

The rim of the bottom is covered with a finely ribbed metal, giving a satin finish effect. The center of the button has a smooth surface raised above the rim and separated therefrom by a ring.

I claim:

The ornamental design for a button, as shown and described.

WALTER FRENZ.
